UNITED STATES PATENT OFFICE.

HERMAN P. BANNINGA, OF MUSKEGON, MICHIGAN.

DUSTLESS ASH SYSTEM.

Application filed October 2, 1926. Serial No. 139,150.

This invention has reference to a nozzle designed for spraying water into the ashpit of a furnace to lay the dust and prevent the dust from passing into the room in which the furnace is positioned, while the ashes are being removed.

An object of the invention is the provision of a novel form of nozzle, so constructed that it will spray substantially the entire ashpit when the valve controlling the passage of fluid through the pipe to the nozzle is moved to allow fluid to pass therethrough.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a sectional view taken on line 1—1 of Figure 2.

Figure 2 is a fragmental elevational view of a furnace equipped with a device constructed in accordance with the invention.

Figure 3 is an elevational view of a nozzle.

Figure 4 is a longitudinal sectional view therethrough.

Referring to the drawing in detail, the reference character 5 indicates the front of a furnace which is supplied with the usual fire door and ashpit door, the ashpit door which carries the nozzle forming the present invention being indicated by the reference character 6 and supported by the hinges 7.

The reference character 8 indicates the supply pipe to the boiler and to which the pipe 9 is connected, the pipe 9 being supplied with a valve housing 10 in which the valve 11 is positioned, the valve 11 controlling the passage of fluid through the pipe 9.

Communicating with the pipe 9 is a pipe 12 that is connected with the pipe 13, through the elbows 14 and 15, there being a substantially short pipe section 16 between the elbows 14 and 15, and with which the elbow 15 has swivel connection.

The reference character 17 indicates a depending pipe connected with the pipe 13 to the elbow 18, which pipe 17 connects with the pipe 19 through the elbow 20. This pipe 19 extends through an opening formed in

one wall of the ashpit door 6 and has an inwardly extended end portion 21 carrying the nozzle 22, to the end that when the door is swung to its open position, the nozzle and communicating pipe will be swung to a position remote from the ashpit door to allow easy access thereto for the removal of the ashes contained therein.

The nozzle forming the invention includes a body portion having a threaded extremity 23 so that it may be secured within one end of a pipe, the nozzle having internal threads 24 to receive the threaded extension of the core 25, which core has a reduced end portion 26 provided with a head 27.

Owing to the construction of the reduced portion 26, it will be seen that a space is provided between the core and inner wall of the body portion defining a passageway to allow fluid to pass from the valve body. A bore 28 is formed in the core and extends to a point substantially intermediate the ends thereof so that it communicates with the transverse bore 29 that in turn communicates with the passageway between the body portion of the nozzle and reduced portion 26 thereof.

As clearly shown by Figure 4, the head 27 is disposed within the confines of a flange 30 which has a substantially short lower side and a substantially wide upper side to the end that the fluid will be directed downwardly and not against the grate bars.

Lateral openings 31 are formed between the flanges to allow the fluid to pass laterally from the nozzle.

From the foregoing it will be obvious that when it is desired to dampen or wet the ashes to lay the dust thereof, it is only necessary to operate the valve member 11 to cause fluid to pass through the nozzle and onto the ashes contained in the ashpit.

After the ashes have been sufficiently moistened, the door may be swung open, moving the nozzle and communicating pipes to a point remote from the ashpit door opening so that the ashes may be readily removed.

I claim:

A nozzle having a tubular body with two forwardly projecting curved flanges of unequal extent in the axial direction of said body, said flanges cooperating to partially define an enlarged continuation of the bore of said body, said flanges being spaced to

form slots communicating with said bore continuation, a removable core snugly fitting and closing the inner end portion of the bore of said body, and spaced from the wall of the outer end portion of said bore, and carrying at its outer end an outwardly flaring head disposed within the said enlarged continuation of said bore and of greater diameter than that of the bore of said body, the

inner end of said core being tubular with 10 lateral outlets leading to the space between said core and the wall of the bore thru said body.

In testimony that I claim the foregoing as my own, I have hereto affixed my signature. 15

HERMAN P. BANNINGA.
